G. R. MARSICO.

SIGNAL.

APPLICATION FILED JUNE 9, 1919. RENEWED AUG. 27, 1921.

1,393,898.

Patented Oct. 18, 1921.

UNITED STATES PATENT OFFICE.

GERARD R. MARSICO, OF BROOKLYN, NEW YORK, ASSIGNOR TO PURITON MANUFACTURING CORPORATION, OF BROOKLYN, NEW YORK, A CORPORATION OF NEW YORK.

SIGNAL.

1,393,898.

Specification of Letters Patent. Patented Oct. 18, 1921.

Application filed June 9, 1919, Serial No. 302,741. Renewed August 27, 1921. Serial No. 496,163.

To all whom it may concern:

Be it known that I, GERARD R. MARSICO, citizen of the United States, and resident of Brooklyn, in the county of Kings and 5 State of New York, have invented certain new and useful Signals, of which the following is a specification.

This invention relates to signals and more particularly to that type shown in my application Serial No. 242,445, filed June 28, 10 1918.

In my co-pending application above identified, use is made of a rotor (preferably heavy) the same having a clutch surface on 15 its interior surface near the periphery thereof and coacting clutch devices operatively related to the clutch surface and adapted to be advanced into driving engagement therewith to cause the rotor to 20 revolve with great force against the diaphragm or vibratory member, the arrangement of parts being such that effective leverage power is created and pulsations of high amplitude set up in the vibratory member or 25 diaphragm. Mechanism is shown for temporarily revolving the clutch devices with the rotor to give the latter its necessary impetus and for subsequently freeing the clutch elements to permit said rotor to 30 revolve by inertia.

In the form of the invention to be described hereinafter in full detail, I have provided a combination of elements, essentially consisting of a rotor and a mating 35 clutch device, the former having an annular exterior clutch surface directly at its periphery. The coacting clutch device is mounted independently of the rotor and the same is designed whereby it can be moved 40 radially with relation to said exterior surface and respectively brought into and out of driving engagement therewith. Means are also incorporated in the described instrumentalities for causing the clutch device to 45 positively revolve with the rotor through that period of time which I find desirable to produce driving force for the rotor and permit it to operate with greater effectiveness against the diaphragm. The relation 50 of parts as established through this arrange-

ment is such that the clutch device is effectively disposed directly at the periphery of the rotor and when it is advanced against said periphery and revolved with the rotor, the force of the latter against 55 the diaphragm is appreciably increased over that produced in my former application and sound of greater intensity produced and a higher number of disturbances communicated to the diaphragm, with the result that 60 better propagation of the sounds created will be present.

Means are also provided for eliminating undue friction between the movable parts of the structure to enable the rotor to 65 revolve for a longer period of time, spending its entire energy against the diaphragm.

Among other features of novelty which will present themselves as the nature of the invention is better understood, I have 70 resorted to the use of a minimum number of parts and have arranged the same, one with another so that the cost of manufacture of the device will be greatly reduced.

The various important features will be particularly pointed out hereinafter in connection with a detailed description of a preferred embodiment of my invention which I have selected for illustration in the 75 accompanying drawing, in which similar reference characters indicate corresponding parts in the several views.

In the drawings,

Figure 1 is a vertical section through the 80 signal, showing parts in full lines, and,

Fig. 2 is a side view of the rotor diagrammatically illustrating different positions of the clutch device.

Fig. 3 is a side view of the eccentric ring 85 and clutch device and,

Fig. 4 is a side view of the eccentric disk.

In my co-pending application Serial No. 242,445, filed June 28, 1918, I have described a signal structure wherein means are employed for disturbing the diaphragm to greater advantage than was possible in mechanically actuated signals heretofore. Through the arrangement of instrumentalities as set forth in said application, I am 95 100

able to minimize suppression of the rotor by the elimination of undue friction and thus cause the rotor to spend great force against the diaphragm with a resulting production of a loud note of desirable pitch and intensity. I further intensify the pitch of the note by shifting the clutch mechanism of the rotor to a point near the periphery thereof and thereby cause applied-rotor-working 10 or transmitting force to exert its full energy against the diaphragm. This latter feature when taken in combination with a rotor of relatively heavy construction gives magnitude to the momentum of said rotor and 15 enables the latter to operate by inertia for an appreciable interval.

In the form of invention which I will now describe, I have elaborated upon the principle above referred to so as to give a 20 wider sound range interval and a greater measure of force of the rotor against the diaphragm.

The advantages of the present construction are attained through the provision of a 25 diaphragm case 5 having a section 6 carrying a resonator 7 and diaphragm 8. Mounted to revolve from a supporting bracket 9 within said case 5 is a shaft 10 carrying an eccentric 11 which consists of a disk 12 fixed 30 to the shaft and a ring 13, encircling the disk and provided with a hanger arm 14. This arrangement imparts rectilinear motion to the hanger arm when the shaft 10 is revolved.

35 Loosely mounted on the shaft 10 is a heavy rotor 15 having an annular exterior clutch surface 16 adapted to co-act with a shoe or element 17 of the hanger arm 14 and thereby cause the rotor to become fixed to 40 the shaft on one actuation of the eccentric. The inner face of the shoe 17 is curved in conformity with the surface 16 of the rotor. The disk 12 is provided with a groove 18, the end walls of which being designed to 45 co-act with the stop lug 19 on the ring 13.

The rotor carries a striking surface 20 adapted to engage with an anvil 21 on the diaphragm to set up disturbances in the diaphragm when motion is transmitted to the 50 rotor.

On the shaft 10 is mounted a fixed gear 55 wheel 22 which meshes with a larger gear wheel 23 on a power transmitting shaft 24. On the shaft 24 is a small gear 25 which intermeshes with a sliding rack bar or plunger 26, the latter mounted in a guide member 27. A spring 28 is employed to normally retain the plunger in a starting position and at the same time retain the gear 60 train in a fixed position whereby to hold the shaft 10 against rotation after power has been transmitted to the rotor.

From the construction described, it follows that when motion is imparted to the plunger to move the same in a downward

direction, power will be transferred to the gear train and in turn to the shaft 10 to revolve the latter in the direction of the arrow "a". In these actuations of the parts above referred to, the eccentric immediately 70 responds to transfer motion to the hanger arm 14, causing the shoe 17 to be advanced into firm clutch contact with the peripheral surface 16 of the rotor. The rotor then becomes fixed to the axle 10 and revolves there- 75 with during the period of downward movement of the plunger 26. The external peripheral contact between the rotor and mating clutch shoe 17, together with the fact that such parts are positioned at a point 80 remote from the center of the rotor gives great leverage action and the rotor is made to act with augmented force against the dia- phragm. As the plunger 26 returns to its normal or starting position, the shaft 10 85 assumes its normal relatively fixed state, and the rotor is again set free to permit the en- tire force thereof to be spent against the dia- phragm. The rectilinear motion of the 90 hanger arm 14 and the stop means 18 and 19 of the eccentric insures active clutch contact between the parts to respectively fix and free the rotor and when the plunger is returned to said starting position, the shoe 17 rests just lightly against the surface 16. Fric- 95 tion between the rotor and said shoe is negligible.

While I have herein fully shown and de- 100 scribed, and have pointed out in the ap- pended claims certain novel features of con- struction, arrangement, and operation which 105 characterize my invention, it will be under- stood by those skilled in the art that various omissions, substitutions, and changes in the forms, proportions, sizes, and details of the 110 device, of the materials used, and of their 115 operation, may be made without departing from my invention.

What I claim as new is:

1. In a device of the class described, a 110 vibratory member, a rotor coacting with said member, said rotor being of large diameter and having an annular clutch surface remotely situated with respect to the sup- 115 porting axis of said rotor, a driven eccentric, and means operated by said eccentric and adapted for driving engagement with said surface to revolve the rotor when motion is transmitted to said eccentric.

2. In a device of the class described, a 120 vibratory member, a rotor coacting with said member, said rotor being of large out- 125 side diameter and having a smooth annular external clutch surface, a driven eccentric, and means operated by said eccentric and adapted for driving engagement with said surface to revolve the rotor when motion is transmitted to said eccentric and including a rocking shoe having a surface conforming with the contour of said surface. 130

3. A device of the class described comprising a diaphragm, a rotor coacting therewith to vibrate the same, said rotor being of large diameter and having an exterior smooth clutch surface, a rotating hanger, a member carried by the hanger and located adjacent to the clutch surface, and means operable on

rotating the hanger for moving the member respectively into and out of engagement with said surface.

Signed at Brooklyn, in the county of Kings and State of New York, this 20th day of May, A. D. 1919.

GERARD R. MARSICO.
